US00D655721S

(12) **United States Design Patent**
Andre et al.

(10) **Patent No.:** US D655,721 S
(45) **Date of Patent:** ** Mar. 13, 2012

(54) **ELECTRONIC DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/390,474**

(22) Filed: **Apr. 25, 2011**

Related U.S. Application Data

(63) Continuation of application No. 29/350,746, filed on Nov. 23, 2009, now Pat. No. Des. 618,205, which is a continuation of application No. 29/341,322, filed on Aug. 4, 2009, now Pat. No. Des. 605,627, which is a continuation of application No. 29/284,190, filed on Aug. 31, 2007, now Pat. No. Des. 598,425, application No. 29/390,474, which is a continuation of application No. 29/352,295, filed on Dec. 18, 2009, now abandoned, which is a continuation of application No. 29/284,268, filed on Sep. 4, 2007, now Pat. No. Des. 606,964.

CLAIM

The ornamental design for an electronic device, as shown and described.

DESCRIPTION

FIG. 1 is a front perspective view of an electronic device showing our new design;

FIG. 2 is a rear perspective thereof;

FIG. 3 is a front view thereof;

FIG. 4 is a rear view thereof;

FIG. 5 is a left side view thereof;

FIG. 6 is right side view thereof;

FIG. 7 is a top plan view thereof;

FIG. 8 is a bottom plan view thereof; and,

FIG. 9 is an enlarged elevational view of a representative corner of the electronic device.

The broken lines show portions of the electronic device which form no part of the claimed design.

1 Claim, 5 Drawing Sheets
